NAIL PULLING TOOL

Calvin G. Formhals, Smithfield, Ill.

Application April 4, 1944, Serial No. 529,523

2 Claims. (Cl. 254—26)

This invention relates generally to the class of tools and pertains particularly to improvements in nail or spike extracting tools such as carpenters' hammers, wrecking bars and the like.

A primary object of the present invention is to provide a nail pulling attachment for a hammer or similar tool, which is designed to give a maximum pulling action with a minimum expenditure of effort and without danger of pulling or breaking off the nail head.

Another object of the invention is to provide a nail pulling attachment for a hammer in the form of a fulcrum lug at the constricted end of the nail engaging claw, with means for receiving the head of a nail when it is in the crotch of the claw, whereby an angular pull will be immediately applied to the nail so as to avoid the possibility of pulling off the head and to immediately loosen the nail so that it may be extracted with a minimum of effort.

Still another object of the invention is to provide in a nail pulling device of the character stated, a novel handle reinforcing means whereby the application of excessive force to the handle will not result in the fracture of the handle adjacent the hammer head, as frequently occurs in connection with ordinary or standard hammers where a relatively short skirt portion extends inwardly around the handle from the handle socket.

The invention will be best understood from a consideration of the following detailed description taken in connection with the accompanying drawing, with the understanding that the invention is not to be confined to a strict conformity with the showing of the drawing but that slight changes and modifications may be made therein so long as such changes and modifications do not depart materially from the invention as expressed in the appended claims.

In the drawing:

Figure 1 is a view partly in side elevation and partly in section of a hammer head constructed in accordance with the present invention showing portion of a handle attached thereto.

Figure 2 is a rear view of the head shown in Figure 1 with the handle removed.

Figure 3 is a detail illustrating a modification of the fulcrum.

Figure 4 is a detail illustrating a further modification of the fulcrum.

Referring now particularly to the drawing the numeral 10 generally designates the head of a hammer of the type commonly used by carpenters, such head including a handle socket

portion 11, at one side of which is formed the driving peen 12 while at the opposite side is the usual claw 13 for extracting nails.

The claw 13 consists of the usual relatively long curved wings 14 between which is the inwardly tapering slot 15 in which is received the body of a nail, the inner end of the slot terminating in the crotch 16.

In accordance with one feature of the present invention, the socket portion 11 of the hammer head is made of materially greater length than normal upon the side of the socket remote from the claw 13 as indicated at 17. Thus the socket is extended upon one side to a greater length than upon the opposite side and this extended portion 17 of the socket forms a reinforcement or brace for the wood handle 18 when force is applied thereto to effect the extraction of a nail from a piece of material. The inner end 20 of the socket or extended portion is cut off obliquely to the length of the socket as indicated at 19, the angle of this end being such that the line thereof substantially passes through the inner end of the claw slot.

In accordance with the present invention there is formed upon the back of the claw 13 at the inner end of the slot 15, the fulcrum body 20 which extends the full width of the head and, in the form illustrated in Figure 1, is formed upon its top side to have the two transverse, spaced ribs 21.

The face of the body 20 nearest the crotch 16 of the nail receiving slot, has a relatively shallow groove 22 formed thereacross and terminates at its inner end in the recess 23, in which recess the crotch 16 of the slot also terminates.

In the use of the nail extractor the portion of the nail adjacent the head will engage in the constricted end of the slot and, in the case of very small nails, will lie within the recess 23 so that when a pull is then applied by rocking the hammer head upon the corner of the fulcrum 20 nearest the nail or the rib 21 nearest thereto, the body of the nail will immediately be bent and some of the pulling force will be transmitted to the body of the nail from the fulcrum instead of being entirely applied to the nail head with the consequent danger of pulling the same off.

50 The side of the fulcrum lug or body 20 nearest the nail is higher than the side farthest away therefrom and consequently the nail will at once be bent around the fulcrum lug so as to get the desired loosening action and pull upon the body 55 rather than upon the head entirely. With this

arrangement a maximum of force can be applied to the nail to effect the smooth extraction thereof from a piece of material, with the application of a minimum of effort to the hammer handle and also without danger of breaking off the nail head.

In Figures 3 and 4 there are shown two modifications of the fulcrum lug, the first figure showing a lug 24 which is flat and square upon its top side while the second figure shows a lug 25 which is rounded or substantially semi-circular. With this form of lug there will be a rolling action as the pull is applied to the hammer handle. Thus there will be less possibility of marring or injuring a surface against which the fulcrum is pressed and would be the case in connection with use of the square lug or the ribbed lug of the first described figure.

From the foregoing it will be readily apparent that the present invention provides a novel and improved means of extracting a nail from materials, wherein greater leverage can be obtained and is obtainable with the ordinary or standard hammer head construction and at the same time, due to the immediate bending of the

nail as the force is applied, pressure is applied progressively along the body of the nail as it is pulled from the material instead of having the entire force applied to the nail head with the consequent danger of pulling off the head, as would be the case if the pull upon the nail were straight instead of in a curve.

I claim:

1. A nail pulling means for a hammer head having a curved claw provided with a tapered nail receiving slot, comprising an outstanding lug formed across the width of the head at the inner end of said slot, said lug providing a fulcrum upon which the head is oscillated in the process of extracting a nail from a piece of material, said lug having a wall immediately adjacent to the inner end of the slot and provided with a nail receiving groove.

2. A nail pulling means as set forth in claim 1, in which the said nail receiving groove terminates at its inner end in an enlarged recess in which the constricted end of the nail receiving slot also terminates.

CALVIN G. FORMHALS.
